UNITED STATES PATENT OFFICE

1,989,706

FLASH LIGHT LAMP DETECTOR

William W. Lillard, Washington, D. C.

Application April 7, 1931, Serial No. 528,368

17 Claims. (CL. 240—2.25)

The present invention relates generally to luminous locators for portable electric lamps and more particularly to locators for the type of portable electric lamps commonly called "flashlight" lamps which employ cylindrical dry cells carried in a tubular shell or housing.

Flashlight lamps are usually "out" or switched off when not in use in the dark, and if laid aside even for a few seconds they are sometimes difficult to find quickly. In many cases, it is very desirable for a person to be able to locate, pick up and use his flashlight, in the shortest possible time.

To facilitate finding a flashlight lamp in the dark quickly, it has been proposed to attach to the shell of the lamp, members bearing spots of radium paint covered by transparent protective window members, all of the elements of the locator device being permanently fastened to the shell of the flashlight. Radium paint of the kind suitable for use in flashlights loses much of its luminosity in three or four years. Hence it is obviously objectionable to permanently attach to a flashlight lamp, locator devices employing such radium paint.

It is an object of my invention to provide inexpensive replaceable locator means for a flashlight which means may be securely mounted on the latter in rigid relation thereto.

Another object of the invention is to provide a flashlight locator unit suitable to replace a rear detachable cap usually found on most flashlights.

According to one way that my invention may be practiced there is mounted on a flashlight rear cap member, a collar member having a portion coated with a luminous radium paint. Simple inexpensive devices including a transparent tubular casing around the collar cooperate with the cap and the collar to form a protective chamber for the luminous locator surface.

A feature of my invention resides in the construction of the constituent parts of the locator device for easy assembly on the flashlight cap without tools. This permits the luminous locator element and the protective members to be bought separately from the flashlight and thereafter to be easily attached to the same by the user.

Another advantageous feature of my invention resides in the provision of means for mounting the transparent window member of my locator device so that the window member can be readily removed for cleaning purposes without tools. Such cleaning is desirable at times, especially since radium paint suitable for inexpensive flashlight locators has a relative-low luminosity and owing

to the smoke and dust often found in the atmosphere in and around cities, the transparency of clear glass or celluloid is sometimes considerably decreased. My window member being easily removable, it can be quickly cleaned without endangering the luminous paint of the locator with cleaning materials.

Other features and advantages of my invention will appear hereinafter.

Referring to the drawing:

Figure 1 represents a longitudinal sectional view of a locator device embodying my invention attached to the rear end of a flashlight lamp shown in part.

Figure 2 represents a flashlight lamp shown partly in perspective and partly in side view and having a locator device similar to the kind shown in Figure 1 attached to the forward end of its shell or housing.

Figure 3 represents a longitudinal sectional view of a two-piece locator unit embodying my invention which is designed to be attached to the rear end of a flashlight lamp.

Figure 4 is a side elevational view, broken away in part of the structure shown in Figure 3.

Figure 5 is a side elevational view, broken away in part of a locator device embodying my invention which is well suited for use in damp places and is designed for attachment to the rear end of a flashlight.

Figure 6 is a rear elevation of the structure shown in Figure 5.

Figure 7 is a longitudinal sectional view through a locator unit employed in the embodiment of my invention shown in Figure 5.

Figure 8 is a rear end view of the structure shown in Figure 7.

Figure 9 represents a partial front view of a flashlight lamp equipped with a locator device embodying my invention which is similar to the device shown in Figure 5 but has a luminous area larger in diameter than the shell of the flashlight.

Figure 10 represents a longitudinal sectional view of the structure shown in Figure 9.

In Figure 1 is illustrated how my invention may be applied to the rear end of a flashlight having a cylindrical tubular shell 11, shown in part and having threads 12 formed in its rear end portion in a usual way. 13 represents a usual cylindrical dry cell.

A locator or detector device made according to one embodiment of my invention for attachment on the shell 11 may include a sheet metal cap member generally designated as 14 which

has adjacent its open end threads formed in its thin wall for engaging in the threads 12. A cylindrical tubular portion 15 of the cap has a forward extension 15E disposed in advance of the threads 12 and has an inside diameter slightly larger than the external diameter of the threads 12. The outside diameter of the extension 15E is slightly less than the outside diameter of the threads in the wall of the cap. The extension 15E is provided mainly to give a better appearance, especially if the cap 14 is used without the other elements of the locator device. To the rear end of the tubular portion 15 is integrally joined a flared portion 16 for a purpose to presently appear. An annular knurled bead or ridge portion 17 having an end wall or closure 18 is integrally joined to the rear and larger end of the flared portion 16.

To inexpensively mount a luminous radium locator element on the cap member 14 in a way so that it can be easily removed and replaced, I provide a ring or collar 19 of paper, fiber or other material suitable for taking radium paint which collar preferably has an inside diameter slightly larger than the outside diameter of the cylindrical portion 15 around which it is disposed.

To protect the luminous substance (not shown in Figure 1) on the collar 19, a tubular casing 20 of celluloid or other suitable transparent material engages around the collar 19, the inside diameter of the casing being slightly larger than the outside diameter of the collar 19. To cooperate with the collar 19 and the casing 20 to form a closed protecting chamber for the luminous locator element on the collar 19, a nut member generally designated as 21 is provided with the internal threads arranged for engaging the threads in the tubular portion 15 and has a downwardly sloping rear portion 22 disposed next to the collar 19. By this construction, a closed chamber for the luminous substance is provided which includes, in effect, a window element—the casing 20—which permits the luminous substance to be seen while helping protect it from injury.

The slopes of the cap portion 16 and the nut portion 21 are preferably the same and in practice will be as small as is practicable. The widths of the collar 19 and the casing 20 are so proportioned relative to each other and to the slopes of the cap portion 16 and nut portion 22 that when the nut is screwed up on the cap far enough both the collar 19 and the casing 20 will be squeezed tightly between the sloping cap portion 16 and the sloping nut portion 22 and also be held apart. By this arrangement, there is formed a substantially airtight compartment or chamber for the luminous radium element on the outer surface of the collar 19.

It can be readily seen that when it is desirable to remove the casing 20 as for cleaning or adjusting it, the cap member 14 may be removed and the nut member unscrewed, both of which operations can be performed easily with one's fingers.

If the collar 19 and the casing 20 should have thick walls, they will preferably have their ends inwardly chamfered to approximately the same slope as the adjoining sloped portions 16 and 22 whereby the collar and the casing will make better fits with the sloped portions. Also, a suitable cement may be applied to the ends of the collar 19 and a casing 20 to help secure an airtight fit with the sloped portions 16 and 20.

By making the slope of the nut portion 22 very slight or gradual the frictional engagement of

the casing 20 on the nut 21 will help hold the latter from becoming unscrewed. The outer periphery of the nut 21 may have knurls (see Figure 2). The outside diameters of the bead 17 and nut 21 will preferably be just slightly larger than the outside diameter of the casing.

To replace the luminous radium element of the detector shown in Figure 1 it is only necessary to screw off the nut 21, remove the casing 20 and the collar 19 which carries the radium element which may be like the element 19R shown in Figure 2. An unused collar 19 may then be slipped on, the casing 20 replaced and the nut 21 screwed up until it binds against the collar and the casing as described above.

The above described construction affords a special advantage, in that it permits a flashlight lamp equipped with only a bare cap member 14 to be purchased and used for a time. Later, if desired, the collar 19, the casing 20 and nut 21 can be purchased and easily assembled on the flashlight without tools of any kind.

The forward side of the nut 21 may have a sloped portion 23 and an undercut 24. In certain cases it may be desired to permanently secure the nut 21 against working loose. This may be done by forming one or more small bumps or knobs 25 in the thin wall of the cap extension 15E to come against the forward side of the nut 21 in the undercut 24. These knobs can be formed by a light blow on a prick punch. A common form of contact spring 26 may be disposed in the cap 14 to make contact between the shell 11 and the cell 13 through the cap member 14.

My invention may be practiced for removably mounting a luminous locator element adjacent the forward end of a flashlight (see Figure 2). A flashlight lamp generally designated as 30 includes a metal shell 31 in which threads 32 may be formed in a usual way in its forward end. A usual rear cap 33 of any desired form may be screwed on the rear end of the shell. A locator unit 34, except as hereinafter noted may be constructed like the assemblage of the cap 14, collar 19, casing 20 and nut 21 to engage the threads 32 for holding the unit on the shell 31. A locator element 19R in the form of a series of dots or a ring or band of radium paint may be carried on the collar 19 around which it may completely extend, a portion of the ring thus being visible from every angle that a person can approach the flashlight 30 when it lies on a roadway or floor.

The forward end of the locator unit 34 has an inreaching lip 36 arranged for holding in place a usual lens 37. It can be seen from inspection of Figures 1 and 2 that the locator unit 34 may be considered a duplicate of the assemblage including the cap 14 except that the extension 15E is omitted and the end wall 18 is partially removed and the remainder formed like the lip 36. It will be understood by those skilled in the art that the incandescent lamp and reflector (not shown) can be mounted in any suitable way in the hollow portion of the locator unit 24 behind the lens 37.

In Figures 3 and 4, is illustrated another form of a locator unit which embodies my invention and is designed for attachment on the rear of a flashlight lamp. A rear cap member generally designated as 40 includes a central cylindrical body portion 41, a rearwardly extending flared portion 43, a knurled bead or rim 44 and an end element 45, all of which parts will preferably be made from a single piece of sheet metal. These

parts, in some cases, may be advantageously made of such material as celluloid, rubber or bakelite.

To engage around the body portion 41, there is provided a transparent casing 46 of glass or celluloid. The luminous element of the locator cap 40 may be a series of dots or spots 46R of radium paint adhering to the inner circumference of the casing 46 and being spaced therearound so that one or more spots will be visible from any direction that a person may approach a flashlight lamp 40L to which the cap 40 is attached.

To inexpensively fasten the casing 46 securely on a cap 40, a short outwardly extending offset 47 is formed in the body portion 41 and next to it is provided an integral cylindrical shelf 48 on which the forward end of the casing 46 is seated. The length of the casing 46 is such that its rear end is disposed against the flared portion 43 when the front end rests on the shelf 48. The material of the cap 40 will preferably be such that it can be easily formed by a spinning operation and the cap 40, and the casing 47 may be revolved on a suitable machine of a well known kind and by spinning operations the rear end of the cap 40 may have the shelf 48 turned outward to engage tightly against the adjacent end of the casing 47. Thereafter a bead portion 49, an end portion 50 and flange portion 51 may be formed as illustrated in Figure 3. It will be understood however, that without departing from the scope of the present invention various changes in the shapes and cross-sections of the elements of the cap 40 may be made for producing a tight seal between the metal portion of the cap 40 and the casing 46.

To increase the effectiveness of the seal between the casing 46 and the metal cap 40 a suitable cement 46C may be applied to ends of the casing just before it is assembled with the metal, and the ends of the casing may be rounded. If made of glass, the casing 46 may be reinforced with metallic wires 52 and 53 embedded therein as illustrated in Figure 4. Threads 54 may be formed in the body portion 41 for engagement with threads (not shown) on the rear end of the flashlight 40L. It will be understood that the body portion 41 may be attached to the flashlight 40L by other well known means besides threads without departing from the scope of my invention.

A ring 55 may be hinged to the rear face of the end 45 for conveniently hanging the flashlight 40L to some object. It can be readily seen that various forms of the ring 55 can be fastened to rear cap members embodying my invention.

In Figures 5, 6, 7 and 8 is shown another embodiment of my invention wherein a removable locator element is mounted inside the cap member having view openings through which a luminous radium element may be seen. A flashlight generally designated as 60 includes a shell 61 having external threads 62 for engaging threads in a cage-like cap member 63 which has a cylindrical body 64 arranged with a series of sight openings in the form of closely spaced slots 64S. An end element 65 of the body 64 may have a number of holes 65H of various sizes arranged in any suitable way to afford a good view of a radium locator element in a bottle-like glass container 66 mounted in the cap member in a way to be presently described.

For mounting the container 66 in the member 63 the latter is made with an inreaching annular bead-like element 67 against which a mounting disc generally designated as 68 is held by means to be presently described. The disc 68

has a concavo-convex body portion 70 of sheet metal out of which is cut a contact spring member 71 (see Figures 5 and 7) which is arranged to press against the rear end of a usual cylindrical dry cell 69 thereby completing the circuit of the flashlight and holding the disc 68 firmly against the bead 67.

To fasten the container 66 in the disc 68, a centrally located round hole is provided in the latter and the container is made with reduced neck member 72 which engages closely in the hole in the disc and passes therethrough. The shoulder formed by making the container 66 with the reduced neck 72 is concavely curved to fit closely against the convex side of the body 70. An annular groove 73 is provided in the neck 72 and mounting lugs 74 integrally joined to the body 70 are so arranged that when pressed inward their ends will be seated tightly against one side of the groove 72 (see Figure 7) and will hold the container securely in position on the disc.

A flange portion 76 of the container 66 may be arranged to receive with a tight fit a glass end member 77 constructed with a recessed central portion in its inner face to leave the remainder 78 of its inner face separate from the central portion. The end member 77 may be cemented with an airtight fit to the flange portion 76. The offset portion 78 of the end member 77 may have a coating 78R of luminous radium paint.

If desired, the end member 77 can be made integral with the flange portion 76 and the paint 78R can be applied through a mouth opening in the neck 72 which opening may be tightly closed with a stopper 79 of cork or other suitable material.

In Figures 9 and 10 is illustrated another embodiment of my invention which is similar to that shown in Figures 5 to 8 inclusive. To a flashlight shell 80, a rear cap member is screwed in a usual way and includes a cylindrical body member 81 having a flange portion 81F and an enlarged cage member 82 which may be fastened to the flange portion by welding or soldering. A bottle-like container 83 which may be constructed similarly to the container 66 carries a luminous radium surface 83R, and may be fastened to a flat circular mounting disc 84 by devices similar to those employed for fastening the container 66 to the disc 68. The disc 84 may be held in place against an inreaching annular bead 81B by a usual contact spring 85 shown in dot-and-dash outlines, which spring engages against a usual dry cell 80B.

It will be noted that the luminous surface 83R has a greater diameter than the body 81. To permit the surface 83R to be readily seen when the flashlight lamp 80 is in certain positions such as when it rests on the floor in a vertical position, view openings 86 are provided in the flange element 81F.

It can be readily seen that the means disclosed herein for mounting a luminous radium element on the rear of a flashlight lamp will function with such a lamp when made with a housing or shell in other than a cylindrical form. In such cases, the rear cap members which carry the luminous elements can be detachably fastened to the shell of the lamp by other devices than screw threads.

Variations may be resorted to within the scope of the invention, and portions of the improvement may be used without others.

Having thus described my invention I claim:

1. A luminous detector for an electric lamp

- including a tubular housing provided with threads in its rear end portion, said detector including a rear cap having a raised annular bead adjacent its rear end and a thin metal wall with 5 threads formed therein for engagement with the threads of said housing, the threads in said cap extending out beyond the outside diameter of said wall, said detector further including a collar member having a luminous portion and engaging 10 around said cap, a transparent tubular casing engaging around said collar, the diameter of said collar member and said casing being smaller than the outer diameter of said annular bead, and a nut threaded to engage the threads on said 15 cap, said collar and said casing arranged for cooperation with said bead and said nut whereby to be squeezed therebetween as said nut is screwed up on said cap for forming a protective chamber for said luminous portion.
- 20 2. A luminous detector unit for a flashlight lamp detector device including a threaded rear cap member for said lamp, a transparent tubular casing engaging around said cap, the inner surface of said casing disposed away from said 25 cap and luminous radium paint deposited on a portion of said inner surface, integral portions of said cap formed for engaging closely against the ends of said casing whereby a closed protective chamber for said radium paint is provided.
- 30 3. A detector device for a flashlight lamp employing dry cells mounted in a cylindrical shell, said device including a protective metal cage member detachably mounted on the rear end of said shell, a closed transparent container in said 35 cage member having a portion of its interior surface coated with a luminous radium paint, means effective for mounting said container in said cage and for making contacts between said dry cells and said shell.
- 40 4. A luminous locator for attachment to a tubular electric lamp housing, said locator including a short tubular body device having means for detachably fastening said device to said housing, a plurality of areas of luminous paint spaced 45 apart around said body device intermediate its ends, a transparent ring-like window member disposed around said body device over said areas, an annular bead member carried by said body device at each end of said window member and arranged to cooperate therewith for forming about 50 said luminous areas a protective chamber extending entirely around said body device, and means effective for releasing the engagement of said bead members with said window member preparatory to removing said window member for 55 cleaning purposes from the vicinity of said luminous areas.
5. In combination, an electric flashlight lamp having a cylindrical threaded shell, a cap device having one end threaded for detachable 60 engagement with said shell, a plurality of luminous areas supported on said cap device and disposed therearound, a transparent cylindrical member engaging around said areas, and a threaded member screwed on the threads in said 65 cap device, said threaded member and said cap device arranged for engaging said transparent member to hold the same on said cap device.
6. A body member for a flashlight rear cap 70 unit which unit includes a collar member carrying luminous locating means and a threaded sleeve member for holding said luminous means on said cap unit; said body member having a cylindrical wall portion and an integral closure 75 therefor at one end thereof, and a raised annular bead around said wall portion adjacent said closed end, the side of said bead opposite from said closed end having a downward taper for engagement with said collar member, said cylindrical wall having threads formed therein adjacent the open end thereof to leave a smooth unthreaded wall portion between said threads and said open end, the internal diameter of said threads being such that said cap unit is made effective to screw on said flashlight shell and the external diameter of said threads being such that said threaded sleeve member may pass over the outer unthreaded wall portion and be screwed on said body member. 80
7. A luminous locator for a portable electric 15 lamp having a tubular housing, said locator including a cap member releasably attachable to said housing, a luminous member carried by said cap member, a transparent window member carried by said cap and cooperating therewith to 20 form a protective chamber for said luminous member in which chamber said luminous member can be readily seen, said window member extending entirely around said cap and releasable means for holding said luminous member and 25 said window member in fixed relation to said cap, said window member being movable angularly with respect to said cap member while engaging therearound and being released therefrom.
8. A luminous locator for a portable electric 30 lamp having a tubular cylindrical housing, said locator including a cap member releasably attachable to said housing, said cap member having a cylindrical wall portion luminous means carried by said cap member, a circular transparent window device for protecting said luminous means, and means for holding said window device in fixed co-axial relation to said cap member, said window device being spaced away from 35 said cylindrical wall portion of said cap member. 40
9. A locator for a portable electric lamp having a threaded tubular housing, said locator including a cap member having a threaded portion for screwing on said housing, said cap member having an annular bead portion adjacent 45 the end of said cap member opposite from said threaded portion, a transparent window member engaging around said cap, the inside diameter of said window member being less than the outside diameter of said bead portion, a nut member screwed on said cap and holding said window member against said bead portion, and areas of luminous paint spaced around said cap under said window. 50
10. A luminous locator for attachment to a portable electric lamp housing, said locator including a tubular body device arranged to be releasably attached to said housing, a plurality of luminous areas spaced apart around said tubular body device intermediate its ends, a transparent tubular window member engaging entirely 60 around said tubular body device, a closure element carried by said body device at each end of said window member and arranged to cooperate therewith for forming a protective chamber about said luminous areas, and means for releasing said window member from said closure elements, whereby said window member may thereafter be removed from around said luminous areas and cleaned without endangering said luminous areas. 65
11. In a luminous locator for a flashlight, in combination, a cylindrical cap member detachably and rigidly fastened on said flashlight, luminous locator means, a closed protective chamber 70

- for said luminous means, said chamber being carried by said cap, and a cylindrical transparent window member for said chamber, the curved periphery of said window member being disposed in parallelism to the curved periphery of said cap adjacent thereto.
12. In a luminous locator for a flashlight, in combination, a cylindrical cap member detachably and rigidly fastened on said flashlight, luminous locator means, a closed protective chamber for said luminous means, said chamber being carried by said cap, and a circular transparent window member for said chamber, said window member being disposed in coaxial relation to said cap member, and the curved periphery of said window member being spaced at all points equi-distant from the curved periphery of said cap member.
13. A tubular cap member for carrying luminous locator elements for use with a flashlight which comprises a plurality of threaded members, said cap member having thread elements for engaging the threaded portion of one of said members, and a cylindrical skirt portion between said thread elements and the open end of said cap member, the inside diameter of said skirt portion being greater than the root diameter of said thread elements, and the outside diameter of said thread elements being greater than the outside diameter of said skirt portion, whereby another of said threaded members may be passed over said skirt portion and screwed on said cap member.
14. A tubular sleeve member for carrying luminous locator elements for use with a flashlight which includes including a plurality of threaded members, said sleeve member having thread elements engageable with the threaded portion of one of said members, and a cylindrical skirt portion between said thread elements and one extremity of said sleeve member, the inside diameter of said skirt portion being greater than the root diameter of said thread elements, the outside diameter of said thread elements being greater than the outside diameter of said skirt
- portion, whereby another of said threaded members may be passed over said skirt portion and screwed on said sleeve member.
15. A luminous locator for attachment to a portable electric lamp housing, said locator including a tubular body device arranged to be releasably attached to said housing, a plurality of luminous areas spaced apart around said tubular body device intermediate its ends, a transparent tubular window member engaging entirely around said tubular body device, and a closure element carried by said body device at each end of said window member and arranged to cooperate therewith for forming a protective chamber about said luminous areas, said window member being adjustable circumferentially with respect to said luminous areas.
16. The combination with a tubular flashlight, of an endless ring member engaging completely around said flashlight, releasable means for holding said ring member on said flashlight in rigid relation thereto, a plurality of luminous elements spaced around said ring member, and transparent protective means for said luminous elements, said luminous elements and said protective means being releasably held on said flashlight in fixed relation thereto by said ring member, said luminous elements and said protective means being separable from each other when removed from said flashlight.
17. In a flashlight, in combination, a tubular member for engaging around said flashlight, said tubular member having an annular bead element adjacent one end thereof, and a threaded portion adjacent the other end thereof, a plurality of luminous elements to be spaced around said tubular member when the same engages around said flashlight, a threaded member arranged to be screwed on said threaded portion, and a tubular support for said luminous elements, said support being disposed around said tubular member and arranged to be releasably gripped between said bead and said threaded member, in rigid relation to said tubular member.

WILLIAM W. LILLARD. 45
